CLAIM

The original design for a cockpit for boats, substantially as shown and described.

DESCRIPTION

FIG. 1 is a perspective view of a cockpit for boats embodying our new design as seen from the stern of the boat;

FIG. 2 is a top plan view of the cockpit of FIG. 1;
FIG. 3 is a side elevation view showing the upper edge of the cockpit as seen from the starboard side of the boat;

FIG. 4 is a side elevation view showing the upper edge of the cockpit as seen from the port side of the boat; and

FIG. 5 is a partial section through the cockpit of FIG. 2 taken on the plane of the line 5—5 of FIG. 2, but with FIG. 5 inverted to show the cockpit pointing in the opposite direction.

The parts shown in phantom lines including particularly the outer hull of the boat are for illustrative purposes only.
